UNITED STATES PATENT OFFICE.

CARL R. SAMUELSON, OF PORTLAND, OREGON.

EXPANDING AND CONTRACTING ROTARY REAMER.

Application filed June 2, 1925. Serial No. 34,322.

My device is generally used in conjunction with well drilling where a casing is inserted and progressed in the well which is being made. Since the drilling operation is carried on beyond the casing and from within and through the same it is absolutely necessary that expanding means be provided that will work by automatic means after the bit has passed below the lowest point of the casing which may be several hundred or thousand feet below the surface of the ground. Under such conditions, means must be supplied that will not easily get out of order. My invention is intended for use in drilling operations wherein drills of the rotary type are preferably used and is especially adapted for use where a casing or well cribbing is being placed as the hole is reamed or enlarged.

20 A further object of my invention consists in an expanding and contracting rotary reamer cutter, the cutting jaws of which expand when the pressure is applied for the forcing of water for drilling operations to the cutting head of the drill.

A further object of my invention consists in simple means for expanding the cutter jaws by hydraulic pressure operating means, causing sloping surfaces to engage with the inner surface of the cutter jaws and expanding the same, and when so expanded, to maintain the same in an absolutely rigid condition. It is not possible to collapse the same until the sloping surfaces contacting with the inner surfaces of the cutter jaws have been released from contact therewith.

With these and incidental objects in view, the invention consists in certain novel features of construction and combination of parts, the essential elements of which are set forth in the appended claims and to a preferred form of embodiment of which is hereinafter shown with reference to the drawings which accompany and form a part of the specification.

In the drawings:—

Fig. 1 is a side elevation, showing the application of my invention as used in the drilling and reaming operation.

50 Fig. 2 is a transverse sectional view of my device, illustrating the reaming and cutting jaws in inoperative position.

Fig. 3 is a transverse, sectional view, illustrating the reaming and cutting jaws in operative position.

55 Fig. 4 is a partial assembly view.

Fig. 5 is a cross section view taken on line 5—5 of Fig. 2, looking in the direction indicated.

Fig. 6 is an enlarged cross section view, 60 taken on line 6—6 of Fig. 2, looking in the direction indicated.

Fig. 7 is a side elevation, illustrating a part of the units and is made to illustrate the method of assembly used in assembling 65 the device.

Fig. 8 is an inside view of one of the split shells.

Like reference characters refer to like parts throughout the several views. 70

My invention consists broadly of upper and lower head members 1 and 2, adapted to a screw connection on the outer ends of the same to the drilling stem, which has been omitted from the drawings for the purpose 75 of clearness. The outer ends of the head members are adapted to threading engagement with split shell members 3 and 4, which are held in intimate engagement along their medial lines by the threading of the 80 two head members thereupon, but as an added safety and to strengthen the same the split shell members are held together by two ring bands 5 and 6. The split shell sides form the frame in which the cutting jaws 85 are supported and the housing into which the full floating automatic actuating mechanism is placed for the distending of the cutting jaws by hydraulic means under pressure. 90

In drilling operations it is the general practice to use casing as the drilling stem through which the operating liquid is pumped under pressure the same being discharged at, or near the head, or point of 95 the drilling-bit and the return of the pumped liquid carries the drilled particles under suspension within the pumped liquid to the surface from where the drilling operations are carried on. My device is connected to 100 the drilling stem on its upper end by the threaded screw joint 7, and to the split shell members by the threaded engagement as shown at 9, the head member is hollow as shown at 8, and adapted to the 105 passage of the liquid being pumped therethrough by the same passing through the hollow floating piston stem 10, having a longitudinal passage therethrough as shown at 11. The gland nut 12, is adapted to the 110 upper ends of the split shells by threaded engagement 14, and the gland nut 12, is so

arranged that suitable packing material 15, may be compressed about the pistoned stem 10, to form a tight hydraulic packed gland between the upper end of the split shell members and the pistoned stem. The upper head member is recessed out as shown at 13, for the reception of the head of the gland nut 12 therein. The lower head member 2, is adapted to the split shell members by 10 threading engagement as shown at 16 and to the lower end of the drill stem by threading screw attachment as shown at 17. The pistoned stem has a piston head 20, disposed near its lower end, and having piston rings 18, disposed thereabout, the piston and piston rings fitting into the cylinder 18, disposed within the lower head and adapted to an accurate and suitable working fit adapted to the close working and operation of 15 the piston within the cylinder where high hydraulic pressures are being used in the operating system. The piston and stem are normally held at the bottom of the stroke through the action of the coil compression spring 19, acting against the upper end of the piston and reacting against the lower ends of the split shell members 3 and 4. A cone shaped slidable head 22, is adapted to the outer pistoned stem and in slidable relation therewith, the same is smaller in diameter below the head and has a recess 23, formed about the restricted diameter disposed below the head and a split sleeve 24, made in two sections, having rings 24^a and 25, formed within the same adapted to fit within the recess 23, on its one end and into a groove within the pistoned stem on the other, the object of the same being to form a flexible connection between the cone shaped slidable head and the pistoned stem. A compression coil spring 27, rests upon the shoulder 28, of the cone shaped slidable head on its one end and upon the upper surface of the sleeve on the other end and there being 40 a space 30, between the lower end of the cone shaped slidable head 22, and the upper end of the split sleeve 24, to form a sliding engagement between the cone shaped slidable head and the pistoned stem. The purpose 45 of this spring and sliding connection between the cone shaped head and the pistoned stem is to provide a flexible shock absorbing connection therebetween, which would lessen the danger of the drilling jaws becoming 50 jammed or injured when they are being extended to an operating position. The central passage 11, through the pistoned stem terminates at its lower end in ports 31 and 32, adapted to discharge the liquids under 55 high pressures at the lower end of the piston head 20, and the pressure within the cylinder will cause the piston and pistoned stem to rise to an operative position, and since the cone shaped slidable head is indirectly connected to the pistoned stem, the same will be 60 raised within certain limits as the piston head is raised. A central bleeder port 33, is formed near the lower end of the pistoned stem terminating in a horizontal opening 34, the object of which is to form an equalizing 70 bleeder port for the drainage of the drill stem and to equalize the pressures that will result as the drilling stem is partially or wholly removed from the well being drilled. A band 35 disposed about the lower end of the pistoned stem is adapted to close the outlet ports leading therefrom excepting that as the pistoned stem is raised the ports 36, disposed within the lower end of the pistoned stem are raised clear of the band 35, 75 and the pumped liquid flows through the cleared ports and is discharged within the lower drilling stem not here shown and to which the drilling bit or head is attached. This position is best shown in Fig. 3. The drilling jaws, as four in number, are shown in Fig. 2 to be in the inoperative position with the cone shaped slidable head and the pistoned stem in the extreme low position, but the same are shown in Fig. 3, to be in 80 raised position wherein the sloping surface 37, of the cone shaped slidable head has contacted with the lower ends of the inner surfaces of the drilling jaws 38, and distended the lower ends of the same. These drilling jaws are preferably made of rectangular stock, that may be shaped at the location of the work and may be made by a smith or other skilled worker without the necessity of highly skilled mechanics or experts for this class of work. When the pumping pressure is cut off the pistoned stem will be 85 returned to the low position as shown in Fig. 2, through the action of the compression spring 19 and the cone shaped sliding head will be lowered and out of intimate contact with the drilling jaws, which will be returned to the normally inactive position. When the drilling stem is raised to 90 the extent that the drilling jaws contact with the well casing and as the drilling stem is raised the inner wall surfaces of the casing will return the drilling jaws to the normal position of being closed, or drawn into the split side walls of the support for the same. The drilling jaws 38, are hinged about the pins 39, and the pins are maintained within drilled holes 40 placed within the wall structure of the split shell members. These pins are so arranged in position that the same 95 tend to lock each other in place when the completed unit has been assembled thus precluding any possibility of the same falling out and thus permitting a release of the drilling jaws which are hinged thereabout. The arrangement of these pins is best shown in Fig. 6, wherein the pins 39 are plain cylindrical members inserted in position and thereafter the pins 39^a are placed in position and the projecting neck 39^b crosses the 100 105 110 115 120 125 130

unclosed opening through which the pin 39 was entered thus locking the same in position. Small openings 40^a connect with the larger opening into which the pins 39 are secured, thus permitting the insertion of a dislodging pin therein to dislodge the pin for removal to permit of the removal of the drilling jaws for renewal or replacement. The drilling jaws may be distended within certain limits. The limits are determined by the contacting of the wing section 41 of the drilling jaws having a sloping surface 42 adapted to seat upon the sloping surface 43, of the wall structure. The limits of distention are determined by the location of these contacting sloping surfaces and the diameter of the conical sliding head, either of which may be varied to meet the operating condition.

20 The ring bands which are preferably placed in position about the split shell members by a pressed fit may be further locked in position by the application of set screws 44 and 45, where one half of the set screw 25 engages the body portion of the split shell member, and the other half engages with one or both ends of the ring band. The set screws may be threaded into the split shell members to a depth greater than that of the 30 thickness of the ring band.

While the form of mechanism herein shown and described is adapted to fulfill the objects primarily stated, it is to be understood that it is not intended to confine the invention to the one form of embodiment herein shown and described, as it is susceptible of embodiment in various forms, all coming within the scope of the claims which follow:

40 What I claim is—

1. An expanding and contracting rotary reamer, comprising split shell members, upper and lower head members adapted to threaded engagement with the split shell members, ring bands disposed about the split shell members and in pressed relation therewith, a hollow pistoned stem running lengthwise of the assembled heads and split shell members and adapted to movement in one direction by a liquid under pressure, a spring placed about said pistoned stem and adapted to return said stem to its normal position when the liquid pressure is released, a 45 slideable head disposed about the pistoned stem and adapted to distend drilling jaws maintained in hinged relationship within the split shell members when the pistoned stem is actuated by a liquid pressure.

2. An expanding and contracting rotary reamer, comprising a body portion formed of split shell members and upper and lower head members, said body portion adapted to threaded engagement with a drilling stem of the rotary type, a hollow pistoned stem disposed within the body portion having

port outlets leading therefrom, said pistoned stem normally held in low position with the port outlets closed and adapted to be actuated into raised position by hydraulic pressure and to open said ports when so actuated, automatic means for returning the pistoned stem to normal position upon the release of the hydraulic pressure; and drilling jaws pivotally mounted within the body portion and adapted to be distended therefrom by said pistoned stem when said stem is in a raised position.

3. An expanding and contracting rotary reamer, comprising a body portion adapted to engage with the drilling stem, a hollow pistoned stem disposed within the body portion adapted to be reciprocated therein, port outlets disposed at the lower end of the pistoned stem, said port outlets being normally closed by an encircling band disposed in fixed position within the body portion, hydraulic pressure means for reciprocating the pistoned stem in one direction and a compression spring for returning the same to normal position and means about the pistoned stem adapted to distend drilling jaws hinged within the body portion when the pistoned stem is reciprocated by the hydraulic pressure means.

4. An expanding and contracting rotary reamer comprising split shell members secured together by upper and lower head members, ring bands disposed about said shell members and in pressed relationship therewith, a pistoned stem slidably maintained within said shell, longitudinal slots disposed in the walls of said shell members, drilling jaws pivotally maintained in said slots, a cone shaped head mounted on said pistoned stem, and adapted to engage with and swing said drilling jaws outwardly when said pistoned stem is in a raised position.

5. An expanding and contracting rotary reamer comprising split shell members, upper and lower head members mounted on said split shell members and securing them in fixed relationship with each other, ring bands mounted about said shell members in pressed relationship therewith, a pistoned stem slidably maintained within said shells, longitudinal slots formed in the walls of said shell members, drilling jaws pivotally mounted in said slots, a cone shaped head mounted about said pistoned stem in limited 115 slideable relationship therewith, a compression spring placed about said pistoned stem, and adapted to maintain it in a normal slidable relationship therewith, a compression spring placed about said pistoned stem, and adapted to maintain it in a normal 120 lower inoperative position, and means to raise said pistoned stem in an operative position and to cause said conical head to contact with said drilling jaws and to swing the same outwardly, comprising a cylinder formed in the lower head member, a piston formed about the lower extremity of said

130

pistoned stem, and slidably maintained in said cylinder, and actuated by fluid pressure.

6. An expanding and contracting rotary reamer comprising split shell members, having threads formed at their extremities, an upper and a lower head member secured to and about the extremities of the said split shell members and in threaded relationship therewith, ring bands placed about said split shell members and in pressed relationship therewith; a pistoned stem slidably maintained within said shells, longitudinal slots formed in the side walls of said shell members, drilling jaws pivotally mounted in said slots, a cone shaped head mounted upon said piston stem, means permitting a limited sliding motion of said cone on said stem, comprising oppositely disposed sleeves, rings on the inner end faces of said sleeves, parallel recesses formed in the pis-

toned stem and the base of the conical head, said recesses adapted to receive the rings of the sleeves therein, and the recess in the head being of a greater width than the ring 25 to be received therein, and a compression spring disposed about said stem, and having one end engaging with a shoulder of the conical head, and the other engaging with a shoulder of the sleeve; a compression 30 spring placed about said piston stem, and adapted to maintain it in a normal inoperative position; and means to raise said piston stem to a position to cause said conical head to engage with said drilling jaws 35 and thereby swing said jaws outward to an operative position, comprising a cylinder formed in the lower head member, a piston formed about the extremity of the said piston stem, and slidably actuated in said 40 cylinder by fluid pressure.

CARL R. SAMUELSON.
